UNITED STATES PATENT OFFICE.

CLINTON R. HANNA, OF WILKINSBURG, PENNSYLVANIA, ASSIGNOR TO WESTINGHOUSE ELECTRIC & MANUFACTURING COMPANY, A CORPORATION OF PENNSYLVANIA.

TELEPHONE INSTRUMENT.

Application filed August 28, 1924. Serial No. 734,606.

This invention relates to sound-reproducing apparatus, such as telephone receivers and loud speakers. More specifically, the invention relates to telephone devices of the type in which the diaphragm is maintained under tension between two magnetic devices.

One object of this invention is to produce a telephonic device which will have a better response to currents of high frequency.

10 A further object of this invention is to provide means by which a thinner diaphragm may be used than has heretofore been possible without introducing instability.

Another object of this invention is to provide means by which a thin diaphragm may be used in telephone devices having much stronger constant magnetic fields than have heretofore been used.

20 A further object of this invention is to provide means by which the resonance frequencies above the fundamental may be moved beyond the range of audibility, without greatly increasing the frequency of the fundamental.

25 Other objects of this invention will be apparent from the following description, when read in connection with the accompanying drawing, wherein:

Figure 1 is a view, partially diagrammatic and partially in section, illustrating one form of my invention,

Fig. 2 is a similar view of a modification.

The diaphragm 1 is of magnetic material, such as mild steel. Any convenient means 35 may be employed for maintaining the diaphragm under tension. The means chosen for illustration include two rings 3 and 4 threaded together. The diaphragm 1 is clamped between the rings 3 and 4. The ring 3 is provided with a flange 5 which projects above the clamping surface. The inner surface of the ring 4, above the clamping face, is threaded to receive a threaded ring 6 provided with a depending flange 7.

40 By screwing the ring 6 into the ring 4, the flange 7 may be made to depress the diaphragm 1 below the upper edge of the flange 5. The extent of this depression regulates the degree of tension. The tension may, 45 therefore, be adjusted by screwing the ring 6 into or out of the ring 4.

A magnet 8 is situated on one side of the diaphragm 1 and a magnet 9 upon the opposite side. These may be either permanent or

electromagnets or permanent magnets reinforced by magnetizing coils. The coil 11 upon magnet 8 and the coil 12 upon the magnet 9 are connected in series through a source of direct current 13 and a rheostat or other regulating device 14. The direction of magnetization in the permanent magnets or the direction of current through the coils 11 and 12 is such that the north pole of the magnet 8 is opposite the south pole of the magnet 9. Consequently, the north pole of the magnet 9 is opposite the south pole of the magnet 8.

A winding 16 upon the magnet 8 and a winding 17 upon a magnet 9, are connected in series, the connection including the terminals 18 by which the signalling current is introduced into the instrument. The direction of the windings 16 and 17 is such that, when the flux due to the magnet 8 is increased by the flux due to the current in the winding 16, the flux in the magnet 9 is decreased by 75 the flux due to the current in the winding 17 and vice versa.

In the form shown in Fig. 2, and inductor 20 is connected across the terminals 18. The source 13 and the rheostat 14 are connected to the center of the inductor 20 and to the connection 21 between the coils 16 and 17. The direction of the windings is such that the current due to the battery 13 produces in the magnet 8 a north pole opposite the south pole which it produces in the magnet 9 and a north pole in the magnet 9 opposite the south pole which it produces in the magnet 8. The signalling current, on the other hand, will strengthen the magnet 8 when it is in the direction to weaken the magnet 9 and vice versa.

When no signalling current is being received, the diaphragm 1 is in equilibrium between the poles of the magnets. Moreover, 95 the magnetic potential of the part of the diaphragm between the two right-hand poles is the same as that of the part between the two left-hand poles. Consequently, the diaphragm carries little or no flux. For this reason, the diaphragm need not be thick and, therefore, need not be heavy.

A thin diaphragm is less rigid than a thick one and a diaphragm, the thickness of which is only sufficient to carry, without saturation, the small flux required by the arrangement just described, would not be sufficiently rigid to be stable.

By turning the ring 6 so that the flange 7 increases the tension upon the diaphragm, a force, due to the elasticity of the diaphragm and tending to restore it to its mid-position when it is displaced, is introduced. This force is in the same direction and of the same phase as the force due to the stiffness of the diaphragm. Stretching the diaphragm by means of the ring 6 is, therefore, equivalent to increasing the rigidity thereof.

When the diaphragm is displaced upward, it is nearer to the poles of the magnet 8. The attraction between the diaphragm and this magnet is, therefore, increased. At the same time the diaphragm is more remote from the magnet 9, and the attraction by this magnet is diminished. The forces due to the two magnets do not balance, therefore, when the diaphragm is displaced. The difference between these forces is in phase with the displacement and in a direction to increase such displacement. Its effect, therefore, is to counteract the reaction due to the rigidity of the diaphragm.

Consequently, by increasing the strength of the magnets, we may produce, in the stretched diaphragm, the effect of a diminution in rigidity. Although the explanation of this effect of the magnets on the apparent rigidity has been made in connection with a diaphragm between two magnets, the effect is also obtained when but one magnet is present, because, even in that case, a displacement of the diaphragm tends to produce a change in the magnetic attraction and this change has the proper phase to tend to counteract the rigidity of the diaphragm.

At certain frequencies, the diaphragm vibrates more in response to the same degree of stimulus than at others. The lowest of these we call the fundamental and the higher ones harmonics although they are not necessarily related in any simple way to the fundamental. Upon stretching the diaphragm the frequency, both for the fundamental and for the harmonics, is increased. The increase in the frequency of the fundamental is not as great as the increase in the frequencies of the several higher resonance periods.

The harmonics are due to a motion of the diaphragm in which it vibrates in a more or less complex fashion. The linear displacement of the diaphragm during such complex vibration is less than for the fundamental. Consequently, the tendency of the magnetic field to counteract the effect of the rigidity due to the stretching is less for the harmonics than for the fundamental.

By counteracting the effect of rigidity, the magnetic field tends to reduce the resonance frequency. The diminution in the frequency corresponding to the fundamental, noticed when the magnetic field is increased is greater

than the corresponding diminution in the frequencies of the harmonics. It is, therefore, possible, by properly relating the tension of the diaphragm and the magnitude of the magnetic field, to have all of the harmonics above the range of audibility and the fundamental not much above its original pitch. This relation may be secured by the design of the instrument or by providing for the adjustment of the constant flux. Such an adjustment is indicated by the adjustable rheostat 14. An adjustment of the position of one or both magnets to vary the air gap would produce the same result.

This leaves the fundamental as the only resonance point within the audible range. The circuit with which the instrument is used may be so designed that the resonance of the instrument at one frequency may be corrected by the resonance of the circuit.

Because this structure enables one to use a diaphragm of smaller mass than has hitherto been possible, the reaction due to inertia is diminished. This reaction is particularly effective at the higher frequencies. The diminution in it, therefore, renders the instrument more effective for high notes.

Although I have illustrated and specifically described but one modification of my invention, it will be apparent to those skilled in the art that many applications thereof are possible. I do not, therefore, intend the specific description to be construed as a limitation. No limitation except that required by the prior art or expressed by the claims is intended.

I claim as my invention:

1. In a telephone instrument, a diaphragm, means for maintaining said diaphragm under tension, said tension being sufficient to bring a resonance frequency of the harmonics of said diaphragm above the range of audibility and magnetic means for counter-acting the effect of said tension upon the fundamental frequency of said diaphragm.

2. In a sound-reproducing apparatus a diaphragm, means for mounting said diaphragm under tension to increase the effective stiffness thereof, magnetic means for producing a displacing effect on said diaphragm which increases with displacement thereof, said tensioning means being so proportioned to said magnetic means that the effect of one upon the fundamental natural period of the diaphragm nearly counterbalances the effect of the other but said effects upon the harmonic natural periods of said diaphragm raise them above the intended range of the apparatus.

In testimony whereof I have hereunto subscribed my name this 22nd day of August, 1924.

CLINTON R. HANNA.
